UNITED STATES PATENT OFFICE

101,662

DESIGN FOR A SPECTACLE FRAME

Raymond L. Wells, Attleboro, Mass., assignor to
American Optical Company, Southbridge,
Mass., a voluntary association of Massachu-
setts

Application July 18, 1936, Serial No. 63,935

Term of patent 14 years

To all whom it may concern:

Be it known that I, Raymond L. Wells, a citizen
of the United States of America, residing at Attle-
boro, in the county of Bristol and State of Massa-
chusetts, have invented a new, original, and orna-
mental Design for a Spectacle Frame, of which
the following is a specification, reference being
made to the accompanying drawing forming a
part thereof.

Fig. I is an enlarged perspective view of a spec-
tacle frame embodying my new design;

Fig. II is a plan view of the spectacle frame
shown in Fig. I with the temples omitted.

Fig. III is a segment of one of the rims on an en-
larged scale.

The characteristic features of my design are
shown in full lines.

I claim:

The ornamental design for a spectacle frame
substantially as shown and described.

RAYMOND L. WELLS.
